Application June 5, 1937, Serial No. 146,653

7 Claims. (Cl. 120—42)

This invention relates to improvements in pens, and more particularly to a magazine pen providing a plurality of pens in one barrel whereby a number of different colored inks are available.

5 An object of the present invention is to provide a plurality of fountain pens within a common barrel, each movable by rotation of the pen unit to an ejecting position where it coacts with an actuator on the barrel by which the selected pen is 10 moved out of the barrel to writing position.

Our invention includes a novel and simple frame structure for supporting a plurality of pens for rotation within a barrel and for movement of a selected one of said pens out of the barrel to 15 writing position.

Another feature of our invention is the arrangement of a plurality of refillable fountain pens within a common barrel each selectively movable to a position for ejection to writing position and 20 each refillable by manipulation of an actuator on the barrel when in said writing position.

Another feature of our invention is the arrangement of three cylindrical fountain pens within a cylindrical barrel which permits each pen to have 25 a diameter substantially equal to the inside radius of the barrel.

Other novel features of pen construction will be apparent from the accompanying drawing and description and the essential features will be 30 summarized in the claims.

In the drawing, Fig. 1 is an elevational view of our novel pen with a portion of the cap broken away; Fig. 2 is a central longitudinal section through the pen of Fig. 1 with the cap removed 35 and a pen in writing position; Figs. 3 and 4 are transverse sections taken along similarly numbered lines of Fig. 2; Fig. 5 is an end view of the pen of Figs. 1 and 2 with the cap removed and all pens in retracted position; while Fig. 6 is a 40 perspective view of the pen carrying frame which in use is housed in the pen barrel.

While our invention may be applied to a magazine pen having a varying number of pens therein, the preferred form is illustrated herewith and 45 comprises three fountain pens 10 housed within a casing or barrel 11 and selectively movable into and out of writing position as desired.

The frame 12 which carries the pens 10 is most 50 clearly shown in Fig. 6. It comprises a plurality of transverse members including the base member 13 and spaced therefrom the members 14 and 15, these latter two being notched to receive the pens 10. Three longitudinally extending rods 16 help 55 to rigidly secure the transverse members in place and serve as guides for the pens 10 during their

sliding movement as will later appear. A central rod 17 also serves as a rigidifying portion of the frame and aids in the positioning of the pens. The base portion 13 is supplied with a cap 13a rigid therewith extending at the rear end of the 5 barrel and serving for manipulation of the frame 12. The base portion 13 carries a plurality of spring pressed detents 18 which when the pen is assembled register with holes 19 in the barrel and hold the frame in any of its adjusted positions. 10

Each pen 10 comprises a cylindrical shell or other suitable framework 20 carrying at one end a pen point 21 which communicates with a flexible ink sack or reservoir 22 preferably of rubber. Each of the pen cylinders has a slot 23 facing outwardly for coaction with a traveling actuator by which the pens are moved longitudinally of the barrel. Each of the cylinders 20 also carries a flexible spring metal piece 24 overlying a slot in the cylinder wall, this being a usual construction 20 by which the spring member is arranged to press inwardly upon the flexible reservoir 22 expelling the air from the reservoir and upon re-expansion of the reservoir it is filled with ink through the point 21 in the well known manner. 25

At its rear end each pen has a plate 25 rigid therewith and having an opening 25a which engages one of the rods 16 so that the pen rotates with the frame 12 but is slidable along its associated rod 16. This construction is shown in Fig. 30 3 where two of the pens are in their retracted position and the third pen is advanced to writing position, but its place when retracted is indicated in dot-dash lines.

On the barrel 11 is slidably mounted an actuator 26 for advancing and retracting each pen selectively out of and into the barrel. This actuator has a portion 26a which enters a guideway 27 on the barrel to guide the reciprocation of the actuator. It also carries a pin 26b which is adapted 40 to engage the slot 23 in a selected pen so that the actuator may move the pen out of the barrel to writing position. The slots 23 when the pens are all in retracted position are aligned with the pin 26b when the latter is in its retracted position as 45 shown in Fig. 1. In other positions of the actuator or pens, the pin 26b will engage the pen cylinders 20 and prevent their rotation within the barrel. The actuator also has a spring pressed detent 26c which is adapted to enter a recess 28 50 in the pen barrel, thus holding any selected pen in its advanced or writing position.

On the forward part of the barrel is a second actuator 29 pivotally mounted on the barrel at 30 and having an end 29a adapted to engage one of 55

the springs 24 when a pen is in writing position and the actuator is moved to the broken line position of Fig. 2. This collapses the ink reservoir 22 for a pen refilling operation. Thus one actuator 5 serves to refill a plurality of pens.

The barrel is closed at its rear end by the base portion 13 and the cap portion 13a of the frame 12. This cap portion may be supplied with markers 31 of a color corresponding to the inks 10 in the associated pens, this marker moving to an indicating position as in Fig. 1 when its associated pen is in position for advancement out of the barrel, which position is indicated by a detent 18 entering one of the holes 19. The other end of 15 the barrel is closed by a molded plastic composition member 32 which is circular in elevation as shown in Fig. 5, except for the opening 32a which corresponds to the outside diameter of a pen cylinder 20 and permits the ejecting movement of a 20 selected pen at this point. A closing cap 33 is provided at the leading end of the barrel and may be secured to the pen in any suitable manner, the form shown comprising a threaded member 25 34 carried by the molded member 32. This molded member also has a recess 32b into which the end of the rod 17 of the frame enters.

In use, the cap 33 is first removed and the end piece 13a is rotated until the marker 31 registers with the arrow on top of the barrel as in Fig. 1, 30 indicating that the pen carrying the proper color ink is in registering position with the opening 32a. This rotation of the frame 12 by the end piece 13a is as previously mentioned only possible when the actuator 26 is in its rearmost position as shown in 35 Fig. 1. With the proper pen so selected actuator 26 is moved forwardly and by the coaction of pin 26b in slot 23 moves the selected pen out of the barrel to writing position as shown in Fig. 2. When any pen is thus in writing position, 40 actuator 29 may be manipulated to refill the pen as already described. When finished with a pen, the actuator 26 is retracted moving the pen again into the barrel, whereupon another pen may be moved to writing position in the same way if desired. 45

What we claim is:

1. In a device of the class described, a barrel, a plurality of fountain pens housed in said barrel and rotatable as a unit relative thereto, means 50 for advancing and retracting each of said pens endwise of said barrel to and from writing position, said means including an actuator carried by said barrel, and a part on each pen selectively movable into position for coaction with said actuator by rotation of said pens in said barrel.

2. A device as in claim 1, wherein said means prevents rotation of said pens in said barrel except when said actuator is in pen-retracted position.

3. In a device of the class described, a barrel, a plurality of fountain pens housed in said barrel and rotatable as a unit relative thereto, each of said pens having self-filling means, and an actuator carried by said barrel and adapted to coact selectively with each filling means when its associated pen registers the same with said actuator by rotation of said pens in said barrel. 5

4. In a device of the class described, a barrel, a plurality of fountain pens housed in said barrel and rotatable as a unit relative thereto, means for advancing and retracting each of said pens endwise of said barrel to and from writing position, said means including an actuator carried by said barrel and a part on each pen selectively movable into position for coaction with said actuator by rotation of said pens in said barrel, each of said pens having self-filling means, and a second actuator carried by said barrel and adapted to coact selectively with each filling means when its associated pen is advanced by said first named actuator to writing position. 10

5. In a device of the class described, a barrel, a frame within said barrel and rotatable relative thereto, a plurality of fountain pens mounted on 25 said frame for sliding movement longitudinally of said barrel, said pen mounting causing said pens to rotate with said frame, an actuator slidable longitudinally of said casing, and a part on each pen selectively movable by frame rotation into 30 coacting position with said actuator, whereby each pen may be moved by said actuator endwise of said barrel to writing position. 35

6. In a device of the class described, a barrel, a frame within said barrel and rotatable relative 35 thereto, said frame having spaced members extending transversely of said barrel and a plurality of rods extending longitudinally of said barrel and rigidly connecting said transverse members, a plurality of fountain pens in said barrel and held by said frame for rotation therewith and slidable longitudinally of said barrel to writing position, each pen having a rigid part 40 slidably mounted on one of said rods, there being an outwardly facing slot in each pen, an actuator 45 slidable longitudinally of said barrel and having a pin adapted to engage in the slot of each of said pens selectively, and said frame having a portion extending beyond said barrel by which said frame may be rotated. 50

7. A device as in claim 6, in which each pen has a flexible refillable reservoir communicating with a pen point, and said barrel carries a refilling actuator adapted to register with each pen when in writing position and to manipulate each 55 flexible reservoir to refill the pen.
